UNITED STATES PATENT OFFICE.

JAMES F. SMATHERS, OF KANSAS CITY, MISSOURI.

TYPE-WRITING MACHINE.

1,227,846.

Specification of Letters Patent.

Patented May 29, 1917.

Application filed November 27, 1914, Serial No. 874,204. Renewed October 19, 1916. Serial No. 126,797.

To all whom it may concern:

Be it known that I, JAMES F. SMATHERS, a citizen of the United States, residing at Kansas City, in the county of Jackson and 5 State of Missouri, have invented certain new and useful Improvements in Type-Writing Machines, of which the following is a specification.

This invention relates to typewriting machines and particularly to the power driven class of such machines, and my object is to provide an improved construction for producing uniform impressions of the type regardless of irregularities in the force or 15 pressure with which the key levers are operated.

A further object resides in the provision of novel means for insuring but a single actuation of each type bar for each depression 20 of its corresponding key lever.

With these general objects in view the invention consists in certain novel and peculiar features of construction and organization as hereinafter described and pointed 25 out in the appended claims, and in order that it may be fully understood reference is to be had to the accompanying drawings, in which—

Figure 1, is a vertical section of a portion 30 of a type-writing machine embodying my invention.

Fig. 2, is a similar section, on a larger scale, and with certain parts in Fig. 1, omitted, and others in altered position.

Fig. 3, is a broken plan view of the parts shown in Fig. 1, but with the type bar removed and its operating lever shown in section.

Fig. 4, is a partly sectional plan view of 40 the parts shown in Fig. 2.

Fig. 5, is a sectional detail of one of the elliptical driving connections.

Referring to the drawings, a driving roller 2 is mounted in the frame 4 of the 45 machine, this roller being driven in the direction of the arrow Fig. 2, from any convenient source of power and provided with any suitable friction surface, such as a rubber sleeve 6 or its equivalent. The key levers are fulcrumed on a transverse bar 10 and held in normally raised position by 50 means of coil springs 12 supported on a transverse bar 14. The type bars 16 are pivoted at 18 in the usual manner and oper-

atively connected with the bell cranks 20 55 pivoted to the bearing bar 22.

My invention resides in the improved connections which I provide for operating these bell cranks from the roller 2 and in the means provided for their control from the 60 key levers.

Each key lever 8 is pivotally connected by a link 24 with a bell crank 26 pivotally mounted on a rod 28 carried by the frame 4. At the side of each bell crank 26 is also 65 pivoted at one of its ends a lever 30, the opposite end of which is pivotally connected by a link 32 to one of the levers 20. Intermediate its ends each lever 30 carries a pin 34 upon which is journaled an elliptical 70 member 36 comprising a pair of elliptical disks connected by a flat hub 38. One of the disks of each member 36 is provided with a pair of pins 40. The hub 38 and pins 40 of each member 36, as shown in Figs. 1 75 and 2, are alined with the major axis of said member. Each pair of pins 40 is designed for engagement with the oppositely disposed pallets 42 of an escapement pawl 44, which is provided with a slot 46 for slidingly mounting the pawl upon a pin 48, on the corresponding lever 30, to the rear of which pin 48 said pawl is pivotally connected to one arm of the corresponding bell 85 crank 26. Each lever 30 also carries a leaf spring 50 which extends in between the disks of the corresponding elliptical member into position to engage the hub 38 without engaging the pins 40 when said elliptical member is rotated, see the dotted lines 90 in Fig. 4.

In the inoperative position of the parts each elliptical member is locked by the escapement mechanism, with its hub 38 holding the spring 50 pressed back under a 95 slight tension. As soon as a key lever is depressed, the connected escapement is released and the elliptical member rotated counterclockwise into engagement with the roller 2. Continued rotation of the elliptical member is then effected through the action of the driving roller with consequent swinging of the lever 30 and operation of the connected type bar. The elliptical member, however, is permitted only a one-half 100 rotation, after which it is relocked by its escapement mechanism until again released by its corresponding key lever.

From the foregoing it will be apparent that I have produced a typewriting machine embodying the features of advantage enumerated as desirable, and while I have 5 illustrated and described the preferred embodiment of the same, I reserve the right to make all changes falling within the spirit and scope of the appended claims.

I claim;

- 10 1. In a typewriting machine having a driving member and movable type-bar operating devices, the combination of an elliptical driven member carried by said devices means tending to rotate said driven member until engaged with said driving member, a double escapement mechanism for normally preventing said driven member from turning, and means for tripping the operative parts of the escapement mechanism to permit the driven member to be turned and for simultaneously causing the other parts of the escapement mechanism to arrest the rotation of the said driven member as the same completes a half revolution.

15 2. In a typewriting machine having a driving member and movable type-bar operating devices, the combination of an elliptical driven member carried by said devices, means tending to rotate said driven member until engaged with said driving member, a double escapement mechanism for normally preventing said driven member from turning, and means for tripping the operative parts of the escapement mechanism to permit the driven member to be turned until engaged and driven by said driving member sufficiently to restore the said means tending to rotate the driven member to operative relation thereto, and for causing the escapement mechanism to arrest the rotation of the driven member before it completes a half revolution.

20 3. In a typewriting machine having a driving member and movable type-bar operating devices, the combination of an elliptical driven member carried by said devices, means tending to rotate said driven member until engaged with said driving member, a double escapement mechanism for normally preventing said driven member from turning,

25 4. In a typewriting machine having a driving member and movable type-bar operating devices, the combination of an elliptical driven member carried by said devices, means tending to rotate said driven member until engaged with said driving member, a double escapement mechanism for normally preventing said driven member from turning, and means for tripping the operative parts of the escapement mechanism to permit the driven member to be turned until engaged and driven by said driving member sufficiently to restore the said means tending to rotate the driven member to operative relation thereto, and for causing the escapement mechanism to arrest the rotation of the driven member before it completes a half revolution.

30 5. In a typewriting machine having a driving member and movable type-bar operating devices, the combination of an elliptical driven member carried by said devices, means tending to rotate said driven member until engaged with said driving member, a double escapement mechanism for normally preventing said driven member from turning, and means for tripping the operative parts of the escapement mechanism to permit the driven member to be turned until engaged and driven by said driving member sufficiently to restore the said means tending to rotate the driven member to operative relation thereto, and for causing the escapement mechanism to arrest the rotation of the driven member before it completes a half revolution.

35 6. In a typewriting machine having a driving member and movable type-bar operating devices, the combination of an elliptical driven member carried by said devices, means tending to rotate said driven member until engaged with said driving member, a double escapement mechanism for normally preventing said driven member from turning, and means for tripping the operative parts of the escapement mechanism to permit the driven member to be turned until engaged and driven by said driving member sufficiently to restore the said means tending to rotate the driven member to operative relation thereto, and for causing the escapement mechanism to arrest the rotation of the driven member before it completes a half revolution.

40 7. In a typewriting machine having a driving member and movable type-bar operating devices, the combination of an elliptical driven member carried by said devices, means tending to rotate said driven member until engaged with said driving member, a double escapement mechanism for normally preventing said driven member from turning,

45 8. In a typewriting machine having a driving member and movable type-bar operating devices, the combination of an elliptical driven member carried by said devices, means tending to rotate said driven member until engaged with said driving member, a double escapement mechanism for normally preventing said driven member from turning,

50 9. In a typewriting machine having a driving member and movable type-bar operating devices, the combination of an elliptical driven member carried by said devices, means tending to rotate said driven member until engaged with said driving member, a double escapement mechanism for normally preventing said driven member from turning,

ing, means for tripping the operative parts of the escapement mechanism to permit the driven member to be turned until engaged and driven by said driving member sufficiently to restore the said means for tending to rotate the driven member to operative relation thereto, and for causing the

relation thereto, and for causing the escapement mechanism to arrest the rotation of the driven member before it completes a half revolution, and means to return the escapement mechanism to its original position to permit said means tending to rotate the driven member to continue the rotation thereof until it completes a half revolution. 60

4. In a typewriting machine, a driving roller, movable type-bar operating devices, an elliptic member journaled on said movable type-bar operating devices, having a flattened hub and a pair of diametrically opposite pins, a tensioned spring exerting pressure on said hub to rotate the elliptic member into engagement with the driving roller, an escapement mechanism engaging one of said pins to prevent rotation of the elliptic member by said spring, means for operating said escapement mechanism to trip it from the path of the engaged pin, to permit said spring to rotate the elliptic member into peripheral engagement with the driven roller to cause the latter by continuing the operation of the elliptic member to effect movement of the type-bar operating mechanism and to effect the retensioning of said spring by said hub; said escapement mechanism being positioned by its operation, to arrest the rotation of said elliptic member after the movement of the type-bar operating mechanism and the retensioning of the spring is accomplished, and means to return the escapement mechanism to its original position to permit said spring to again turn the elliptic member until arrested by the engagement of the other pin with the escapement mechanism.

In testimony whereof, I affix my signature, in the presence of two witnesses. 95

JAMES F. SMATHERS.
